UNITED STATES PATENT OFFICE.

MATTHEW WILSON, OF GARRISON, IOWA.

HARNESS-SADDLE.

SPECIFICATION forming part of Letters Patent No. 697,060, dated April 8, 1902.

Application filed November 7, 1901. Serial No. 81,428. (No model.)

To all whom it may concern:

Be it known that I, MATTHEW WILSON, a citizen of the United States, residing at Garrison, in the county of Benton and State of Iowa, have invented a new and useful Harness-Saddle, of which the following is a specification.

The invention relates to improvements in harness-saddles.

10 The object of the present invention is to improve the construction of harness-saddles, more especially the construction of the back plate or yoke for covering the saddle tree or frame and the side straps, and to provide a 15 simple and comparatively inexpensive one which will increase the strength and durability of the saddle.

The invention consists in the construction and novel combination and arrangement of 20 parts hereinafter fully described, illustrated in the accompanying drawings, and pointed out in the claim hereto appended.

In the drawings, Figure 1 is a perspective view of a harness-saddle constructed in accordance with this invention. Fig. 2 is a longitudinal sectional view of the same. Fig. 3 is a detail perspective view of the back plate or yoke. Fig. 4 is a detail sectional view on the line 4-4 of Fig. 2.

30 Like numerals of reference designate corresponding parts in all the figures of the drawings.

1 designates a back plate or yoke arranged on the upper face of the frame or tree 2 of 35 the saddle and provided with front and rear longitudinal flanges 3 and 4, forming a space to receive the side straps 5 of the saddle and arranged at the opposite longitudinal edges of the frame or tree 2. The rear flanges are 40 arranged at each of the sides or side portions of the plate or yoke and are spaced apart at the top of the same to provide an opening 6, through which extends the loop 7 for the crupper-strap. The front flange is continuous and 45 extends across the center of the yoke or plate along both side portions.

The yoke or plate is provided with openings for the reception of the pad-screws 8 and the shanks of the checkrein-hook and terret- 50 rings, and it is designed to be constructed of

any suitable metal, and its side flanges extend downward to the pad and fit against the top of the same at the front and back of the harness-saddle.

In order to increase the strength and durability of the saddle, the top plate or yoke, which conforms to the configuration of the saddle frame or tree, extends to the end loops 9 of the saddle frame or tree. The loops 9, which extend upward from the saddle frame 60 or tree, receive the side straps of the harness-saddle, and the ends of the plate or yoke are reduced to form tongues 10, which extend through the loops and which are preferably rounded, as shown. The ends of the front 65 and rear side flanges are cut away at opposite sides of the yoke or plate and form shoulders at the inner ends of the tongues, which greatly increase the strength and durability of the saddle by being extended through and 70 engaged with the end loops of the saddle frame or tree.

It will be seen that the back plate or yoke is simple and comparatively inexpensive in construction and adapted to be readily applied to a saddle, that it extends from one end loop of the saddletree to the other, and that by being interlocked with the said loops the strength of the saddle at the top is greatly increased.

80 What I claim is—

In a saddle, the combination of a saddletree provided with upwardly-extending transversely-disposed end loops, and a yoke consisting of a top plate provided with side 85 flanges and having longitudinal extensions or tongues projecting through the end loops and secured to the saddle by the same, said tongues being arranged in the same planes as the adjacent portions of the said plate and 90 formed by reducing the same, substantially as described.

In testimony that I claim the foregoing as my own I have hereto affixed my signature in the presence of two witnesses.

MATTHEW WILSON.
